UNITED STATES PATENT OFFICE.

ISAAC HAMMER, OF NEW YORK, N. Y.

LOCK.

1,280,993

Specification of Letters Patent.

Patented Oct. 8, 1918.

Application filed December 22, 1917. Serial No. 208,437.

To all whom it may concern:

Be it known that I, ISAAC HAMMER, a citizen of the United States, and a resident of the city of New York, borough of the Bronx, in the county of Bronx and State of New York, have invented a new and Improved Lock, of which the following is a full, clear, and exact description.

Among the principal objects which the present invention has in view are: To prevent tampering with the lock when actively disposed; to provide a relatively rigid construction; to prevent rattling of the lock when actively disposed; and to strengthen the resistance of the lock.

Drawings.

Figure 1 is a side elevation of a lock constructed and arranged in accordance with the present invention, the lock being shown partly in section, the section being taken as on the line 1—1 in Fig. 2;

Fig. 2 is a horizontal section of the lock shown in Fig. 1, the section being taken as on the line 2—2 in said Fig. 1;

Fig. 3 is a perspective view showing in detail the lock and shackle plate therefor.

Description.

As seen in the drawings, the lock has a continuous body casing 8. The casing 8 is preferably constructed from metal which is by preference cast. By thus constructing the casing, a solid striker portion 9 is provided having extended therein parallel sockets 10, which open from one side of the casing. The sockets 10 are traversed by perforations 11.

The perforations 11 are formed through both walls of the sockets 10 and are provided to receive the bolts 12. The bolts 12 are rigidly connected by a sliding guide plate 13 with which is integrally formed a ward plate 14, in which one or more wards 15 are formed. The ward plate 14 and bolts 12 connected therewith are reciprocated to pass the bolts through the sockets 10 and perforations 11 in the outer wall thereof, as seen best in Fig. 1 of the drawings, or to retract the same so that the ends of the bolts 12 are withdrawn from the sockets 10, as shown in Fig. 3. To this end, a key 16 is inserted or maintained in the casing 8, and within the ward 15. In the drawings, the key 16 is of a permanent type and is connected by means of a shank 17 with a handle 18. The key 16

is so arranged that when the handle 18 is rotated to the limits of its action, the key 16 presses on one or the other side wall of the ward 15 to shoot or withdraw the bolts 12. At the limit of each of the thrusts of the key 16, the end thereof rests on one or other of the approximately vertical sections 19 of the wards 15. The shank 17 is mounted in the casing 8 and approximately in line 65 with the sections 19 of the ward plate 14, so that if the handle 18 is not operated after the bolts 12 have been moved to either of the extreme positions mentioned, the key serves as an abutment to prevent the movement of 70 the ward plate 14 by other means than that afforded by the key and the handle 18 thereof.

When the bolts 12 are "shot" or disposed in active service, they extend through holes 20 in the shackles 21. The shackles 21 are 75 integrally formed with the striker plate 22. The striker plate 22 is angular in form as seen best in Fig. 2 of the drawings, and the panel 23 thereof in service is held on the door jamb by screws inserted through 80 screw-holes 24. The panel 23, as shown best in Fig. 2 of the drawings, is covered by the door 25, when said door is closed.

As shown best in Fig. 2 of the drawings, when the lock is actively disposed, the bolts 85 12 are protected from interference or tampering, by reason of the fact that they are inaccessible from outside the door 25, or by a tool forced between said door and the jamb on which the striker plate 22 is 90 mounted.

It is also obvious that the lock or door cannot be forced without shearing the bolts 12, as they are held in the perforations 11 and holes 20 of the striker portion 9 and shackles 95 21. At the same time, it is equally evident that when the key 16 is operated by turning the handle 18 associated therewith, the bolts are readily and easily withdrawn. It is further evident that the simplicity of construction of the lock permits the parts thereof to be made substantial and strong.

Claims.

1. A lock comprising a striker portion 105 having rectangular recesses therein, said recesses opening toward the frame for the door to which said lock is attached, the sides of said striking portion being perforated in lines transverse to said recesses; a striker 110 plate adapted to be structurally attached to said frame, said plate having a plurality of

- rectangular shackles extended from said plate to enter said recesses, said shackles having perforations extending therethrough, said perforations being adapted to align with the recesses in the sides of said striking portion of said lock when said lock is closed on said striking plate; a plurality of bolts slidably mounted in said perforations for extension therethrough; and means for moving said bolts through said perforations for withdrawing the same therefrom, said means embodying a rotary device having a thrust member operatively engaging said bolts.
2. A lock comprising a striker portion having rectangular recesses therein, said recesses opening toward the frame for the door to which said lock is attached, the sides of said striking portion being perforated in lines transverse to said recesses; a striker plate adapted to be structurally attached to said frame, said plate having a plurality of rectangular shackles extended from said
- plate to enter said recesses, said shackles having perforations extending therethrough, said perforations being adapted to align with the recesses in the sides of said striking portion of said lock when said lock is closed on said striking plate; a plurality of bolts slidably mounted in said perforations for extension therethrough; and means for moving said bolts through said perforations for withdrawing the same therefrom, said means embodying a ward plate rigidly attached to said bolts and having a ward formed therein, and a key rotatably mounted in said lock operable exteriorly thereto, said key being adapted for engagement with said ward for moving said plate and bolts attached thereto, said key being pivoted adjacent the horizontal plane of the open end of the sides of said ward for forming a stopping member therefor.

ISAAC HAMMER.
